UNITED STATES PATENT OFFICE.

GEORGE L. VOGEL AND ANTHONY FINCK, OF JERSEY CITY,
NEW JERSEY.

MACHINE FOR BENDING ANGLE-IRONS.

SPECIFICATION forming part of Letters Patent No. 761,429, dated May 31, 1904.

Application filed October 10, 1903. Serial No. 176,518. (No model.)

To all whom it may concern:

Be it known that we, GEORGE L. VOGEL and ANTHONY FINCK, citizens of the United States, residing in Jersey City, in the county of Hudson and State of New Jersey, have invented certain new and useful Improvements in Machines for Bending Angle-Irons, of which the following is a specification.

This invention relates to certain improvements in machines for bending angle-irons, T-bars, Z-bars, and similar structural shapes, the machine being designed so as to inclose the angle-bars by two sets of rolls—a horizontal set and a vertical set adjacent to the horizontal set and at right angles thereto, but in such a manner that each set of rolls receives a direct positive motion by suitable transmission from the driving-shaft, so as to fully inclose the angle-iron and force it through between the two sets of rolls without being distorted or warped; and for this purpose the invention consists of a machine for bending angle-irons, which comprises a set of bending-rolls, a set of guide-rolls mounted to revolve in a plane at right angles to the plane of the bending-rolls, each set comprising a pair of outer rolls for engaging one side of the angle-iron, and an intermediate third roll for engaging the opposite side thereof, the rolls of one set being arranged adjacent to the corresponding rolls of the other set, and mechanism for transmitting direct positive motion in proper direction to each roll.

The invention consists, further, of the combination, with the two sets of bending and guiding rolls, one set being arranged at right angles to the other set of rolls and each consisting of a pair of outer rolls and an intermediate third roll, of mechanism for imparting positive motion to each roll of both sets and mechanism for adjusting some of the rolls of each set so as to permit the bending of the angle-iron to different degrees of curvature; and the invention consists, lastly, of certain additional details of construction and combinations of parts, which will be fully described hereinafter and finally pointed out in the claims.

In the accompanying drawings, representing

a machine embodying our invention, Figure 1 is a side elevation of our improved machine for bending angle-irons. Fig. 2 is a vertical transverse section on line 2 2, Fig. 1, showing one of the guide-rolls meshing with one of the bending-rolls and showing the adjustment of these rolls. Fig. 3 is a perspective view of an angle-iron after being curved by our machine. Fig. 4 is a horizontal section on line 4 4, Fig. 1. Fig. 5 is a front elevation, partly in section, through a portion of the machine. Fig. 6 is a vertical longitudinal section on line 6 6, Fig. 4. Fig. 7 is a fragmentary vertical transverse section on line 7 7, Fig. 4, and Fig. 8 is a detail view of the adjustable transmitting-gear for the intermediate roll of the horizontal set of bending-rolls as viewed from line 8 8 of Fig. 4.

Similar letters of reference indicate corresponding parts.

Referring to the drawings, A, B, and C represent three upright standards suitably bolted to the floor. A is the front standard, and B the intermediate and C, the rear standard, of the supporting-frame. The standards are approximately of the same size and shape and having some portions broken out for permitting access to the mechanism between the separate standards. Two sets of rolls are employed—a bending set consisting of two lower rolls D D' and an upper roll D" and a guide set consisting of three rolls, two rolls of which are on one side of the iron, while the third roll is on the other side of the same. For rectangular angle-irons the bending-rolls are arranged horizontal and the guide-rolls are arranged vertically thereto. All the rolls are driven by positive motion, whereby the angle-iron is moved from one end of the machine to the other and bent in a reliable and effective manner to the curvature desired. The adjacent ends of these rolls are provided with bevel-gears, so that rotary motion is imparted by direct transmission from the primary rolls to the supplemental rolls adjacent thereto. The left-hand primary roll is mounted on a shaft S, to which motion is imparted by a belt-and-pulley transmission from an overhead shaft, the belt being thrown to a

loose pulley by suitable shifting mechanism (not shown) when the motion of the machine is to be interrupted or moved from the loose pulley to the fast pulley when motion is to be imparted to the bending-rolls. The driving-shaft S is supported in journal-bearings of the three standards A, B, and C. On the front end of the driving-shaft and on that part of the driving-shaft located between the standards B and C are mounted transmitting gear-wheels g, which transmit motion by intermediate gear-wheels g⁵ to gear-wheels g³ on the shaft S' of the outer primary bending-roll D', so that rotary motion in the same direction as the primary roll D is imparted to the second primary roll D'. The shafts of the intermediate transmitting-gears g⁵ are supported on stud g⁴, connecting straps g' g², that are mounted, respectively, on the driving-shaft S and the auxiliary shaft S', as shown in Fig. 4. By the two sets of transmitting-gears g g⁵ g³ on the shafts S S' a uniform motion parallel with each other is imparted to the primary bending-rolls D D', and thereby to the supplemental rolls G G', which are placed in mesh with the same.

The intermediate primary bending-roll D², mounted on shaft S², receives motion from the primary driving-shaft S by intermediate transmitting-gears f f' f² f³. These transmitting-gears are shown clearly in Fig. 8 and are arranged for the purpose of permitting the adjustment of the intermediate primary bending-roll D² to any position within certain limits parallel with the rolls D and D' and still the gears be in mesh, so as to be rotated from the driving-shaft S. For this purpose an elbow-shaped strap f⁵ is journaled on the shaft S and has its other end pivoted by stud f⁷ to strap f⁶, which latter is journaled on shaft S². A gear f is secured on shaft S adjacent the elbow-strap and meshes with a gear f', journaled at the bend of said strap. A gear f³ is secured on shaft S² adjacent the link f⁶, and a gear f² is journaled on stud f⁷ and meshes with both gears f' and f³. As the shaft S² of the intermediate primary bending-roll D² is made vertically adjustable within certain limits, so as to permit the bending of angle-irons of different heights, the journal-bearings of the roll D² have to be adjusted in the guide-openings of the standards A, B, and C. By the adjustment of the shaft S² of the roll D² the intermediate gears and their straps are correspondingly adjusted, while they are always retained in mesh with each other and the gear-wheel f⁵ on the driving-shaft S, so that whatever be the position of the roll and the shaft continuous rotary motion is imparted to the same from the driving-shaft S. On the rear end of the shaft S² is mounted a gear-wheel p, which meshes with a gear-wheel p' on a shorter shaft S', which is supported in journal-bearings of the rear standard C and in bearings of an auxiliary support B', which is guided in the opening of the

intermediate standard B, said shaft S' serving to transmit, by means of bevel-gears p² p³, direct positive motion to the intermediate vertical roll G², as this roll cannot receive motion from its primary roll, for the reason that it has to be adjusted relatively to the same. The guide-roll G is rotated from roll D by bevel-gear d⁶.

By the sets of transmitting gear-wheels described direct rotary motion is imparted to the primary bending-rolls D D' D² and by the bevel-gear transmission between the primary and supplemental rolls D G and D' G' rotary motion to the outer supplemental rolls G G', while independent rotary motion is imparted to the intermediate primary roll D² and to the intermediate supplemental roll G² from their transmitting-gears; but all the primary rolls are rotated by the transmitting gear-wheel mechanism described in the same direction, and also the supplementary rolls, so as to act simultaneously on opposite sides of the angle-iron that is fed and moved forward between the rolls and produce the coaction of all the rolls on the same and the bending without lateral dislocation or warping of the angle-irons. The bending and guiding rolls act simultaneously by their positive rotary motion on the angle-irons and produce the bending of the same in a reliable and effective manner according to the curvature to which the rolls are adjusted.

For the purpose of bending the angle-iron to any desired degree of curvature the outer right-hand primary and supplemental bending-rolls D' G' are made adjustable both in vertical and horizontal direction by the adjusting mechanisms shown in Fig. 6. The roll D' is for this purpose supported in a journal-bearing which is made adjustable in horizontal direction by a screw-spindle m³, which is swiveled to the journal-bearing of the shaft S' and which is guided in a stationary nut m², attached to a bracket m, as shown in Fig. 4. The screw-spindle m³ is turned by a suitable handle so as to permit the easy adjustment of the primary bearing of the shaft S'. These bearings are guided in larger oblong guide-frames m', that are guided in vertical ways of the standards A and B and that are adjusted vertically on said ways by a screw-spindle n, that is swiveled to the under side of said guide-frames, to which rotary motion is transmitted by a bevel-gear n' n², of which n' is provided with a screw-nut meshing with the screw-spindle n, while n² is placed on a shaft n³, that turns in bearings at the lower part of the standards A and B, as shown in Figs. 5 and 6. By these adjustable guide-frames the journal-bearings of the shaft S' and the roll D' can be adjusted in both vertical and horizontal direction, according to the curvature imparted to the angle-iron. The vertical roll G' is supported in bearing-block d⁶, that is made a part of the journal-bearings of the primary roll D'. 130

Hence the supplemental roll G' is simultaneously adjusted with the primary roll D', as will appear from detail Fig. 2.

The intermediate rolls G² and D² of both sets of rolls are adjusted independently of each other. As the journal-bearings of the shaft S² of the primary roll D² are supported in the guide-openings of all the three upright standards A B C, it is necessary to simultaneously adjust these bearings. This is accomplished by means of screw-spindles *i*, that are swiveled to the upper end of the journal-bearings h² and h³ of the shaft S² and guided in sleeves h at the upper ends of the standards A B C, said sleeves carrying worm-gears l, that mesh with worms l' on a horizontal worm-shaft l'', as shown clearly in Fig. 5. By turning the crank-handle l³ the three journal-bearings are simultaneously turned in the same direction, and thereby the roll D² raised or lowered as required by the curvature to be imparted to the angle-iron. For the purpose of adjusting simultaneously the roll G² of the supplemental set of bending-rolls the entire journal-bearings of the shaft S² in the standard B is provided with a U-shaped extension at its upper side, in which the upper angular end of the auxiliary support B' is received. The U-shaped extension is connected by a set-screw p⁶ with the rearwardly-projecting upper end of the support B', so that the latter is moved with the intermediate bearing of the shaft S² in upward or downward direction. As the bearings of the auxiliary shaft S³ are located in the standards B and C, the rear bearing is connected with the rear bearing of the shaft S², and thereby the shaft S³ is raised or lowered simultaneously with the transmitting bevel-gear p² p³, so that at whatever point the supplemental roll G² is adjusted relatively to and with the primary roll D² the motion-transmitting mechanism will act on the shaft of the roll G², which is supported in neck and step bearings of the support B', as shown in Fig. 7. As it is necessary, however, to impart a certain degree of adjustment to the supplemental roll G² in forward or backward direction, the vertical support h³ can be adjusted by the set-screw, the inner end of which is swiveled to the upper angular end of the support, while the shaft S³ is connected by a spline with the pinion of the bevel-gear, and the support B' can be moved with the roll D² and the bevel-wheel in forward and backward direction, so that the supplemental roll G² remains in adjustment with the primary roll D², so that they bear on the side and end of the angle-iron to be bent and produce thereby the hugging of the same on its bottom, sides, and ends, so as to keep it within full control during its motion through the primary and supplemental bending-rolls at whatever curvature the outer right-hand bending-rolls and intermediate bending-rolls are adjusted.

Having thus described our invention, we

claim as new and desire to secure by Letters Patent—

1. In a machine for bending angle-irons, the combination of a primary set of bending-rolls, a supplemental set of guiding-rolls, mounted to rotate in a plane at an angle with the primary set of rolls, each set comprising two rolls for engaging one side of the angle-iron, and an intermediate third roll for engaging the opposite side thereof, the rolls of one set being disposed adjacent to the rolls of the other set, and means for adjusting one of the end bending-rolls in two different paths each transverse to its axis, substantially as set forth. 75

2. In a machine for bending angle-irons, the combination of a primary set of bending-rolls, a supplemental set of guiding-rolls mounted to rotate in a plane at an angle with the primary set of rolls, each set comprising two rolls for engaging one side of the angle-iron and an intermediate third roll for engaging the opposite side thereof, the rolls of one set being adjacent to the rolls of the other set, and means for adjusting each roll of one end pair of adjacent rolls in two different paths transverse to their respective axes, substantially as set forth. 80 85

3. In a machine for bending angle-irons, the combination of a primary set of bending-rolls, a supplemental set of guiding-rolls mounted to rotate in a plane at an angle with the primary set of rolls, each set comprising two rolls for engaging one side of the angle-iron and an intermediate third roll for engaging the opposite side thereof, the rolls of one set being disposed adjacent to the rolls of the other set, and means for simultaneously adjusting one end pair of adjacent rolls in different paths transverse to their respective axes, substantially as set forth. 90 95 100

4. In a machine for bending angle-irons, the combination of a primary set of bending-rolls, a supplemental set of guiding-rolls mounted to rotate in a plane at an angle with the primary set of rolls, each set comprising two rolls for engaging one side of the angle-iron and an intermediate third roll for engaging the opposite side thereof, the rolls of one set being disposed adjacent to the rolls of the other set, means for adjusting the end pair of adjacent rolls, means for adjusting the intermediate pair of adjacent rolls, and means for driving the bending and guiding rolls from the shaft of one of the end bending-rolls, substantially as set forth. 110 115 120

5. In a machine for bending angle-irons, the combination of a primary set of bending-rolls, a supplemental set of guiding-rolls mounted to rotate in a plane at an angle with the primary set of rolls, each set comprising two rolls for engaging one side of the angle-iron and an intermediate third roll for engaging the opposite side thereof, the rolls of one set being disposed adjacent to the rolls of the other set, means for adjusting one of the end pair of ad- 125 130

- jacent rolls, means for adjusting the intermediate pair of adjacent rolls, and motion-transmitting means for driving the intermediate bending-rolls from the shaft of one of the end bending-rolls in the various positions of adjustment of said intermediate roll, substantially as set forth.
6. In a machine for bending angle-irons, the combination of a primary set of bending-rolls, a supplemental set of guiding-rolls mounted to rotate in a plane at an angle with the primary set of rolls, each set comprising two rolls for engaging one side of the angle-iron and an intermediate third roll for engaging the opposite side thereof, the rolls of one set being disposed adjacent to the rolls of the other set, means for adjusting one of the end pair of rolls, means for adjusting the intermediate pair of adjacent rolls, and motion-transmitting means arranged to drive the bending-roll at one end from the shaft of the bending-roll at the other end in the various positions of adjustment of the former end roll, substantially as set forth.
7. In a machine for bending angle-irons, the combination of a primary set of bending-rolls, a supplemental set of guiding-rolls mounted to rotate in a plane at an angle with the primary set of rolls, each set comprising two rolls for engaging one side of the angle-iron and an intermediate third roll for engaging the opposite side thereof, the rolls of one set being disposed adjacent to the rolls of the other set, means for adjusting one of the end pair of rolls, means for adjusting the intermediate pair of adjacent rolls, motion-transmitting means between the said end bending-rolls comprising gears on the shafts of both bending-rolls, a pair of links pivoted on the shaft of each of said rolls and connected by a stud-shaft, and a gear on the stud-shaft meshing with the gears of the end bending-rolls, substantially as set forth.
8. In a machine for bending angle-irons, the combination of a primary set of bending-rolls, a supplemental set of guiding-rolls mounted to rotate in a plane at an angle with the primary set of rolls, each set comprising two rolls for engaging one side of the angle-iron and an intermediate third roll for engaging the opposite side thereof, the rolls of one set being disposed adjacent to the rolls of the other set, means for adjusting one of the end pair of rolls, means for adjusting the intermediate pair of adjacent rolls, motion-transmitting means between one end bending-roll and the intermediate bending-roll comprising an el-
- bow-shaped link pivoted to the shaft of the end roll, a strap pivoted to the shaft of the intermediate roll and to the other arm of the elbow-shaped link, a stud-shaft connecting the elbow-shaped link and strap, a gear at the angle of said elbow-shaped link, a gear on the stud-shaft meshing with the said gear on the elbow-shaped link, and a gear on the shaft of the intermediate bending-roll and meshing with the gear on the stud-shaft, substantially as set forth.
9. In a machine for bending angle-irons, the combination of a primary set of bending-rolls, a supplemental set of guiding-rolls mounted to rotate in a plane at an angle with the primary set of rolls, each set comprising two rolls for engaging one side of the angle-iron and an intermediate third roll for engaging the opposite side thereof, the rolls of one set being disposed adjacent to the rolls of the other set, means for adjusting the end pair of rolls, means for adjusting the intermediate pair of adjacent rolls, and means for adjusting the intermediate guiding-roll relatively to its adjacent bending-roll in the various positions of the latter, substantially as set forth.
10. In a machine for bending angle-irons, the combination of a frame, a primary set of bending-rolls mounted on the frame, a supplemental set of guiding-rolls mounted on the frame to rotate in a plane at an angle with the primary set of rolls, each set comprising two rolls for engaging one side of the angle-iron and an intermediate third roll for engaging the opposite side thereof, the rolls of one set being disposed adjacent to the rolls of the other set, the frame comprising three upright members, a journal-block arranged to slide vertically in each of said members, a shaft rotatable in said blocks, said intermediate bending-roll being mounted on said shaft and said intermediate guiding-roll being carried by one of said blocks, a screw-spindle swiveled to each of said journal-blocks, and a worm-shaft on the frame arranged to rotate the screw-spindles simultaneously, substantially as set forth.
